CLAIM

The ornamental design for a breast milk collector, as shown and described.

DESCRIPTION

FIG. 1 is a top, front, right side perspective view of a breast milk collector showing the design;

FIG. 2 is a bottom, rear, left side perspective view of the breast milk collector of FIG. 1, showing the design;

FIG. 3 is a front elevation view of the breast milk collector of FIG. 1, showing the design;

FIG. 4 is a rear elevation view of the breast milk collector of FIG. 1, showing the design;

FIG. 5 is a left elevation view of the breast milk collector of FIG. 1, showing the design;

FIG. 6 is a right elevation view of the breast milk collector of FIG. 1, showing the design;

FIG. 7 is a top plan view of the breast milk collector of FIG. 1, showing the design; and,

FIG. 8 is a bottom plan view of the breast milk collector of FIG. 1, showing the design.

The broken lines shown in the drawings depict portions of the breast milk collector that form no part of the claimed design.

1 Claim, 8 Drawing Sheets
